UNITED STATES PATENT OFFICE.

HUBERT R. HUMPHREY, OF KALAMAZOO, MICHIGAN, ASSIGNOR TO GENERAL GAS LIGHT COMPANY, OF KALAMAZOO, MICHIGAN.

GAS HEATER.

Application filed January 22, 1926. Serial No. 83,038.

The main object of the invention is to provide an improved gas heating stove which is very efficient and highly attractive in appearance.

5 A further object is to provide an improved gas heating stove which is well adapted to be mounted upon a wall and is also adapted for use in bathrooms and the like.

Objects pertaining to details and economies of my invention will definitely appear from the detailed description to follow. The invention is clearly defined and pointed out in the claims.

15 A structure embodying the features of my invention is clearly illustrated in the accompanying drawing forming a part of this application, in which:

Fig. 1 is a front view of my improved heating stove, a portion of the front panel 20 being broken away.

Fig. 2 is a vertical section on a line corresponding to line 2—2 of Fig. 1.

Fig. 3 is a horizontal section on a line corresponding to line 3—3 of Fig. 2.

25 Fig. 4 is a detail vertical section on a line corresponding to line 4—4 of Fig. 3.

In the embodiment illustrated I provide a casing comprising a back wall 1, end walls 2, a top 3 and a bottom 4, these parts as illustrated being sheet metal stampings. The back wall is provided with bead-like rolls 5 at its vertical edges which are engaged by bead-like rolls 6 on the rear edges of the end walls 2. The top and bottom overlap 35 the edges of these walls as shown in Fig. 2, and the parts are secured together by bolts 7 arranged through these beads and engaging the top and bottom walls, clamping the parts together. These parts are substantially 40 shown in my copending application.

Within the casing I mount a base plate 8 having a curved flange or roll 9 at its front edge embracing the bead-like roll 4' of the bottom wall 4.

45 Upon the casing I mount a reflector 10 which has end portions 11 which extend forwardly to the panel 12 of glass, preferably a translucent or opalescent glass; that is, it is preferably not clear glass through which the 50 radiating elements 13 may be visible. The lower edge of this panel 12 is seated in a groove 14 provided therefor in the base plate 8, while its upper edge is engaged in a groove 15 in the flue member 16 arranged upon the 55 upper edge of the reflector. The forward

edge of the flue member has a roll or bead 17 therein which is engaged by a curved flange or bead 18 on the top wall.

Bolts 19 are arranged through these beads to engage the finishing members or uprights 60 20 having ears 21 at their ends overlapping the ends of these beads, thereby securing the parts in assembled relation. This provides a closed chamber above the base plate in which the radiating elements are supported. 65 A vent opening 22 is provided for this chamber.

The burner 23 is arranged in the casing below the base plate 8 and has tips 24 disposed in coaxing relation to the radiating 70 elements 13. The bottom wall 4 of the casing has openings 25 which are preferably provided with a screen 26. The top wall 3 has air circulating passages 27 therin, there being a space 28 between the reflector and the 75 rear wall so that air may circulate between the reflector and the rear wall, and out the top of the casing.

With this arrangement of parts I provide a heater of high efficiency and one which is 80 very attractive in appearance, the entire front of the casing being illuminated and the radiant heat being reflected from the radiants and by the reflector through this panel.

While I have illustrated my improvements 85 as I have especially designed the same for wall heaters, they are well adapted and desirable for embodiment in other types of heaters, that is, heaters adapted to be set into fireplaces or portable heaters and the like. 90

Having thus described my invention what I claim as new and desire to secure by Letters Patent is:

1. In a structure of the class described, the combination of a casing comprising a 95 back wall and end walls and a top and a bottom, said top and bottom walls having air inlet openings therein, a base plate disposed within said casing in spaced relation to the bottom providing a burner chamber, 100 a flue member disposed within said casing in spaced relation to the top thereof and having a vent opening at one end thereof, a reflector disposed within said casing between said base and flue member in spaced 105 relation to the casing back and end walls providing an air circulating space from the burner chamber around the reflector and flue member, a transparent front panel disposed between said base and flue member 110

and coacting therewith and with said reflector to provide a closed radiating element chamber, said base and flue member having grooves receiving the top and bottom edges of said front panel, said reflector having in-turned supports for said panel, casing uprights disposed on the front edges of said end walls and overlapping the edges of the front panel, a radiating element disposed in said radiating element chamber, and a burner disposed in said burner chamber in coacting relation to said radiating elements.

2. In a structure of the class described, the combination of a casing open at the front and comprising top and bottom walls having air inlet openings therein, a base plate disposed within said casing in spaced relation to the bottom thereof, a flue member disposed within said casing in spaced relation to the top thereof and having a vent opening through the casing, a reflector disposed within said casing between said base and flue member and in spaced relation to the walls of the casing permitting circulation of air around the same, a transparent front

panel disposed between said base and flue member and coacting therewith and with said reflector to provide a closed radiating element chamber, a burner disposed below said base plate, and a radiating element disposed in said radiating element chamber in spaced relation to said burner.

3. In a structure of the class described, the combination of a casing open at the front, a base plate at the bottom of said casing, a flue member disposed horizontally at the top of said casing, a reflector disposed within said casing between said base plate and flue member, a translucent panel disposed between said base and flue member and coacting therewith and with said reflector to provide a closed radiating element chamber, a burner disposed below said base plate, and a radiating element disposed in said radiating element chamber in coacting relation to said base plate.

In witness whereof I have hereunto set my hand.

HUBERT R. HUMPHREY.
